UNITED STATES PATENT OFFICE

144,219

DESIGN FOR A JEWELRY DISPLAY BOX

Hubert Ropp, Lake Bluff, Ill., assignor to F. H. Noble & Company, Chicago, Ill., a corporation of Illinois

Application September 12, 1945, Serial No. 122,030

Term of patent 14 years

(Cl. D80—5)

To all whom it may concern:

Be it known that I, Hubert Ropp, a citizen of the United States, residing at Lake Bluff, in the county of Lake and State of Illinois, have invented a new, original, and ornamental Design for Jewelry Display Box, of which the following is a specification, reference being had to the accompanying drawing, forming part thereof.

In the drawing:

showing my new design; Figure 2 is a rear perspective view of the same; Figure 3 is a front elevational view of the jewelry display box with the cover in raised position; Figure 4 is a side elevational view of the same; and Figure 5 is a front perspective view of the same.

I claim:

The ornamental design for jewelry display box, substantially as shown.

HUBERT ROPP.
